Des. 221,586
Patented Aug. 24, 1971

221,586

STEAM/AIR FINISHING CABINET

Richard H. Dison, 214 N. Broadway,
Rochester, Minn. 55901

Filed June 15, 1970, Ser. No. 23,497

Term of patent 3½ years

Int. Cl. D15—05

U.S. Cl. D49—1

FIG. 1

FIG. 2

FIG. 3

FIG. 4

FIG. 1 is a view in perspective as seen from one side, one end and top of a steam/air finishing cabinet showing my new design;

FIG. 2 is a view in side elevation thereof the side opposite that shown in FIG. 1;

FIG. 3 is a view in end elevation thereof as seen from left to right of FIG. 2; and

FIG. 4 is a view in top plan thereof.

The bottom not shown is substantially devoid of ornamentation.

I claim:

The ornamental design for a steam/air finishing cabinet, substantially as shown and described.
